UNITED STATES PATENT OFFICE

EUGENE W. CARUTHERS, OF SECANE, PENNSYLVANIA

RAIL SPLICE BAR AND RAIL JOINT

Application filed May 9, 1928. Serial No. 276,348.

My invention relates to the spliced joints between the successive rails of a railroad track.

A purpose of my invention is to provide a splice bar joint that will be contained between the outer edges of the rail flange and having its head portion, which engages the under side of the rail head, relatively heavier than its foot portion, which engages the rail flange, the center of gravity axis of the splice bars upon opposite sides of the rails being nearer the head of the rail than the flange thereof.

A further purpose is to provide a splice bar joint that does not extend outwardly beyond the rail flanges and that has its upper section modulus greater than its lower section modulus, the section modulus being taken with respect to a horizontal plane through the center of gravity axis of the bars.

A further purpose is to use different contours of splice bars and different lengths and areas of bolts to accommodate differences in service conditions and differences in the characteristics of the bolt stock and in the characteristics of the splice bar stock.

A further purpose is to provide splice bars having a greater weight of metal above the axes of the bolts than below their axes in order better to receive the impacts from the rails.

A further purpose is to make the location of the splice bar web depend upon service conditions and elastic characteristics of the bolt and bar stocks. I vary the distances between the rail web and bar webs according to these conditions and characteristics.

A further purpose is to provide the foot portion of splice bars with lateral extension sufficient to avoid any material local distortion of the bar when tightening the bolts but not greatly in excess of this amount.

A further purpose is to provide interfitting arcuate bearing surfaces between the splice bars and bolt members that clamp the bars to place upon opposite sides of rails.

A further purpose is to optionally use washer members for providing stiffening rib supports to the flange portions of a splice bar. I provide a washer formed to make a tight-

ening fit between the flange portions of a splice bar so that when the bolt is tightened the flanges are supported near their outer edges against opposite sides of the washer.

A further purpose is to shorten the effective length of track bolts that fasten splice bars to place by setting the nut directly on the web of one of the bars and giving the nut an extended portion for a wrench hold. I am in this way able to give the head and foot portions of the splice bar considerable lateral extension while placing the splice bars relatively close to the railweb.

A further purpose is to provide a nut member between the head and foot flanges of a splice bar with a square wrench hold beyond the flanges.

Further purposes will appear in the specification and in the claims.

I have elected to show a few only of the many different forms of my invention, but have selected forms that are practical and effective in operation and which well illustrate the principles involved.

Figures 1 to 4 are vertical sections through different forms of rail joints embodying my invention, Figure 3 showing also an optional spiking to a tie at the joint.

Figure 3^a is a fragmentary vertical section showing a reversal of the nut in Figure 3 along with the use of a slightly longer bolt.

Figure 5 is a reduced scale broken side elevation of structure shown in Figure 3.

Figures 6 to 9 are vertical sections showing other forms of joints embodying my invention, Figures 8 and 9 also illustrating different desirable ways of spiking the joint to ties, and Figure 9 also showing a form of the tie plate beneath the splice bars of the joint.

Figures 10 and 11 are a plan view and a side elevation respectively of Figure 9.

Like numerals refer to like parts in all figures.

Describing in illustration and not in limitation and referring to the drawings:—

In the past it has been customary to laterally extend the splice members of a rail joint outwardly beyond the rail flanges, and it has also been strongly urged for effective place-

ment of the metal in the splice bars so that the upper and lower section moduli of these members shall be substantially equal.

I have found it better to keep the splice bars inside the outer lines of the rail flange, and also have discovered that a more effective placement of the metal in the splicing members is one that makes the upper section modulus of the members greater than their lower section modulus.

The theory that the upper and lower section moduli of the splicing members should be the same has been based upon a mistaken assumption that a solution of how to most effectively place the metal involves merely shaping the bars like beams to effectively support bending moment stresses that are alternate tension and compression in the head of the bar with corresponding alternate compression and tension stresses in the foot of the bar.

The beam strength of the upper portion of a bar may be considered as determined by the upper section modulus which is the moment of inertia of the whole bar, divided by the distance from a horizontal plane through the bar's center of gravity axis to the uppermost fiber of the bar, while the beam strength of its lower portion is determined by the same moment of inertia divided by the distance between the lowermost bar fiber to the same horizontal plane through the center of gravity axis of the bar.

The upper and lower section moduli of a bar are equal when its center of gravity axis is midway between the uppermost and lowermost bar fibers.

As a matter of fact the stresses in the bar members are of widely different character and relative importance according to differences in service conditions that depend upon many variant factors; such as the effectiveness of the support given by the individual ties, the elastic and dimensional characteristics of the bolt stock, the elastic and form characteristics of the bar stock, the tightness of the nuts as determined perhaps by the length of time from the last tightened, or perhaps by the personal equation of a workman who did the last tightening, by the extent of any permanent set in the bolts or in the bars, and by the character and magnitude of the rolling loads that must be supported, whether or not these give an excessive pounding action or whether pounding is not excessive.

The impact stresses due to pounding of the wheels are in practice variant but nearly always very heavy. These impact stresses are absorbed throughout the whole section of the bar but are absorbed more at the head than at the foot, and this determines the need for making the head heavier than the foot.

The bending stresses of alternating compression and tension in the bars are very

much less if the bars are maintained tightly in place at the adjoining ends of the rails, the bars which support the ends of the adjoining rails from relative movement then being subjected to very heavy shearing stresses.

The effectiveness of the supporting contact at the rail ends may be, and usually is, much greater after the nuts of the splice bars have been tightened.

After the nuts have been tightened the effectiveness of contact gradually lessens until by the time the bolts are about to be again tightened the engagement between the bars and rails may be quite considerably less effective.

Obviously these changes in the effectiveness of engagement between the bars and rails widely change the character of stresses in the bars and in the rail ends, and I aim to lessen the deterioration in the effectiveness of the joints by selecting bolt dimensions to accommodate variant elastic properties of the bolt stock, and by selecting a contour of bar to accommodate variant service conditions and the variant properties of the bar stock.

Almost any one of the different forms illustrated may be preferable to any of the others under some conditions of service, the contour of bar, length and diameters of bolts that are best for example with one set of service conditions being inferior for use with a different set of conditions, and, vice versa, splicing members that are inferior with one set of conditions may be the best for another set of conditions.

Referring to Figure 5 which while the side elevation of Figure 3 may be taken as typical of the other forms, the adjacent ends of rails 10 and 11, supported upon suitable tie-plates 12 and 13 and ties 14 and 15, are held together intermediate the ties by preferably interchangeable splice bars 16 and track bolts 17 and 18.

The track bolts 17, adjacent the rail ends, are under more severe strains and stresses than the bolts 18 near the ends of the splice bars and for this reason I prefer to use bolts that are more perfectly elastic and of greater effective length at 17 than are necessary for the bolts 18.

The selection of the track bolts should be one of properly balancing considerations of price and better adaptation to meet the intended service conditions. Naturally the bolts that are more perfectly elastic are relatively high in price, being for example made of alloy steel, such as a chrome-nickel steel, while the more usual and cheaper bolts are of carbon steel.

I prefer to place the cheaper type of bolt at 18 where the strains and resultant stresses are less severe, and to provide more perfectly elastic and effectively longer bolts at 17 near

the ends of the rails where the strains and stresses are relatively large and where it is important that there should be an adaptation to repeatedly yield or strain with little or no resultant permanent set.

5 In the past the bolts 17 and 18 have been alike and interchangeable, while I preferably make these bolts different in sectional size or effective length, either or both, as by cutting the stress down in bolt 17 to a value

10 within which the bolts are perfectly elastic by a suitable increase in size and then obtaining the adaptation to yield by a suitable increase in the effective length of the bolt.

15 I may use bolts at 17 and 18 that are dimensionally the same but of different elastic properties, as by using a nickel-chrome steel bolt at 17 and a carbon steel bolt at 18.

20 In Figure 5 the bolts 17 are shown as the two bolts nearer to the rail ends, while the bolts 18 are the two bolts farther away from the rail ends. These are thus illustrated because I wish to point out further how they can be given different strengths or resilience 25 to advantage in improving the strength or service of the joint or in reducing the cost. One of the ways in which the bolts may differ to advantage is in their effective lengths. This is illustrated in a comparison of Figures 3 and 3^a. With the same shape and size 30 of splice bar the bolt 18 in Figure 3 is made effectively short by engagement of the thread 20 in the nut 21 with the bolt thread close up to the splice bar. The counterbore in the 35 nut is shown as outwardly facing.

As contrasted with this, the bolt 17 is shown 40 in Figure 3^a to be effectively long because the same nut is reversed to face the counterbore toward the splice bar and to bring the threaded part of the nut toward the outside. The bolt in Figure 3^a is shown as actually 45 longer than that in Figure 3 in order to have it engage the full length of the thread. The nuts may be square or hex interchangeable.

45 I have provided the head 22 (Figure 1) with an inwardly extending heel 23 in a position to ultimately engage the web 24 of the rail after the bar has been in service a considerable period.

50 I have also provided the upper inwardly directed corner 25 of the head with a radius of curvature that is equal to or greater than but not less than that of the rail fillet 26, and have given the foot 27 a contour such as to 55 adapt it during continual service to gradually ride inwardly up the flange portion 28 of the rail after further inward movement of the bar head has been stopped by the bar head engaging the rail web.

60 A forward relief of the foot at 29 should be sufficient to permit the more central portion 30 of the foot to ride up the rail flange and an outer relief of the foot at 31 should be sufficient to avoid stopping the bar from 65 the desirable vertical canting.

This type of bar maintains a live joint connection between the bar head and rail head out beyond the rail fillet after as well as before the head, through a continued service of perhaps several years, engages the rail

70

web, the bar foot being pulled gradually further inwardly after further inward movement of the head has been stopped and the rail fillet being freed from engagement with the bar head by reason of the canting and upward movement of the bars when the bolts are tightened after the bar heads have come against the rail web. I have disclosed and claimed this feature in my application for rail joints, Serial No. 276,847, filed May 9, 1928, 80 copending herewith.

75

I preferably provide interfitting arcuate bearing surfaces between the splice bars and bolt members in that these interfitting arcuate surfaces permit changing the angular alignment of the bars, without effecting material distortion strains and stresses in the bolts or in the web portions of the bars.

85

These surfaces include interfitting arcuate bearing surfaces between the bolt head and one splice bar and other similar interfitting arcuate bearing surfaces between the bolt nut or bolt washer and the other splice bar.

90

The arcuate interfitting surfaces between the bolt member and the splice bars may be of either spherical or cylindrical contour, either form having advantages, and each in certain cases being the more desirable. Both forms permit the bars to cant without an introduction of uneven stresses and strains either in 100 the bolt or in the bar.

95

It will be understood that the interfitting arcuate surfaces are spherical when they comprise surfaces that are rounded in all directions, i. e. that form portions of spheres; and 105 that the interfitting arcuate surfaces are cylindrical when they are rounded in one direction only, the surfaces then corresponding to portions of interfitting cylinders.

105

When the surfaces are spherical they are 110 adapted to tilt relatively in any direction, and when they are cylindrical they are adapted to tilt in one direction only.

110

In practice the tilting is frequently in one direction, being that due to the gradual tilting of the splice bars due to wear and take-up on the bolts.

115

Sometimes the operating conditions are such that the bolts and splice bars at the joints relatively tilt in one or more other directions, due for example to the bending of the bolts incident to rail creeping, and in this event it will be more desirable to use the spherical form of interfitting surfaces.

120

An arcuate cylindrical concavity 32 along the outside of the splice bar web gives a section that is easily rolled and one having least thickness of metal along the middle of the web which is in accord with efficient placement of the metal.

125

130

A convexly curved bolt head 33 fitting the cylindrical surface of the web and a convexly curved washer surface 34 fitting the other cylindrical surface are both surfaces that are very easily formed when manufacturing the bolts and washers respectively.

Interfitting cylindrical bearing surfaces are not well adapted to relative rotation, and for this reason washers are needed under nuts 10 when the interfitting bearing surfaces are made cylindrical.

There are some advantages in making the interfitting arcuate bearing surfaces between the bolt members and bars spherical instead of 15 cylindrical and when this is done the washer under the bolt may be omitted, the inner end 35 of the nut 21 being formed with a spherical bearing surface 36 to seat in a corresponding spherical depression on the web of the bar.

20 The omission of the washer shortens the effective length and therefore the requisite length of the bolt and proportionately shortens any permanent set of the bolt during service, incidentally also shortening the total 25 elongation.

The shorter bolt will be preferable or not according to circumstance.

If the bolt be of highly elastic stock, that is, if it will not take any material permanent 30 strain, the strain disappearing if and when the stress is removed and the strains and stresses remaining continually proportional, it may be advantageous to have the bolt long 35 because of the resultant relatively great total elongation when the nuts are tightened, in that the very perfect elasticity of the bolts then maintains a very uniform pressure against the splice bars, resulting in a very live joint.

40 On the other hand when bolts are made of a more usual stock that is only imperfectly elastic they take a permanent set when tightened and it is then desirable to limit the bolt elongation to a definite value in that this 45 limits a corresponding undesirable permanent set of the bolt.

It will be evident that the total permanent set of a bolt incident to a given total pull will vary directly with the effective length of the 50 bolt, and that a shorter bolt must also be sectionally smaller if its permanent set is to be the same as that of a longer bolt subjected to the same total longitudinal pull, for the same length of time. The permanent set is 55 a function of the length and sectional area of the bolt, of the total pull upon the bolt, the duration of the pull, and of the properties of the material of the bolt.

I may accommodate the sectional area of 60 the track bolts to their effective length, using shorter and optionally smaller bolts when conditions are such that it is desirable to limit the total elongation of the bolts when the nuts are tightened to a definite value, or using 65 longer bolts when conditions make it desir-

able to have a fairly high elongation which is usually only the case when the material of the bolt is such as to very perfectly maintain strict proportionality between longitudinal stress and longitudinal stretch without any substantial permanent set when the stress has been removed.

It may sometimes be desirable to reduce the stress in the bolts to a definite value below which it has been found stress and strain are substantially perfectly proportional and in this event the sectional area of the bolt is determined by the total longitudinal pull from tightening the nuts while the length may be desirably increased to increase the liveness of the joint by increasing the bolt's elongation.

When conditions make it desirable to use long bolts I may use washers under the nuts as in Figures 1, 2, 4 and 6, and use a form of splice bar having web portions spaced far from the web of the rail, either or both, (Figures 1 and 7).

If conditions make it desirable to use short bolts I avoid the use of washers (Figures 3 and 8) and form the splice bars with webs relatively close to the rail web.

It will be seen that the spherical bearing surfaces between the bar and nut members are preferable when shorter bolts are desirable.

It is obvious that the advantage of making the bearing surfaces between the bars and bolt members of an interfitting arcuate contour is one that avoids uneven stresses and strains in the bolts and in the webs of the bars when the bars are relatively canted and also one that avoids uneven stresses in the bolt if the bolt becomes bent, which is not at all unusual.

Bolts become bent during service most frequently in a direction longitudinal of the rail, 10 the bending being due to stresses tending to pull the rails apart longitudinally.

When a bolt becomes bent longitudinally of the rail the spherical seating of the nut and head members are preferable to the cylindrical, in that the spherical seating more effectively avoids uneven stresses and strains when the bolts are tightened.

In the form shown in Figure 1 the head is shown materially heavier and therefore 11 stronger than the foot. The foot is perhaps unduly light unless the joint has a bottom tie-plate under the rail flange, as in Figures 9 to 11, or unless the bolts are from bars of exceptionally good stock, when the form should be 12 particularly advantageous, as the greater section modulus of the head as compared to that of the foot should be very effective in absorbing impact stresses due to the pounding action of the wheel.

The bar head has to be strong enough to stand up under these impact stresses which have a relatively smaller effect at the foot portion of the bar.

Both the head and foot must have a con- 13

siderable strength against horizontal distortion when the bolts are tightened, that is, should have reasonably high section moduli with respect to a vertical plane through the center of gravity axis of the bar.

This strength in horizontal direction should be sufficient to prevent any distortion of the bars along their lengths incident to tightening the bolts and for this reason the foot will often need to be fairly heavy, but less heavy than the head.

The actual dimensions of both foot and head ought to vary according to service conditions. Both should be heavy enough to meet the intended service without bending inwardly at the bolts when the nuts are tightened, but preferably the foot portion should not be heavier than is needed to do this.

In Figure 2, I show a form of bar having a relatively large foot section, a foot section almost as heavy in fact as the head section.

The pounding action of the wheels is a widely variant factor, increasing probably directly with the speed and weight of trains and with the extent the running wheels are out of perfect balance and perfect roundness and also without doubt varying with the solidity of rail support presented by the road bed.

In subsequent figures I vary the position of the splice bar web to vary the bolt characteristics. This and the inventions affecting the bolt seat and bolt characteristics cooperate of course with any type of head and foot splice bar flanges whether they extend beyond the rail flanges or not but cooperate best with the splice bar flanges shown.

In Figure 3 I have moved the web portion of the bars inwardly as compared to that of the bars shown in Figures 1 and 2 and have also made the foot portion large as compared to that of Figure 1 though less heavy than that of Figure 2.

The line 37 between the bearing surfaces at the foot and head respectively here passes through the web portion of the bar. The outward overhang of the head and foot flanges at 38 and 39 respectively is quite considerably greater than in the form shown in Figure 1, and I provide a long nut 21 that extends outwardly from the bar web 40 to present a wrench hold 41 suitably beyond the outer edges of the flanges 38 and 39, and may provide the nut interior at any portion of its length with an enlarged unthreaded portion 19, optionally varying the position of the threaded portion 20 along the length of the nut in order to accommodate the effective lengths of the bolts to differences in service conditions.

The nut member of Figure 3 may be turned end for end for use with bolts of different effective lengths, either end of the nut being adapted to make spherical bearing engagement with the spherical seat on the bar web.

A very short bolt may mean a bolt of lesser requisite sectional area size as well as of lesser length. This is because it may be desired to limit the permanent set in the bolt to a definite maximum value which would be secured by a sectionally smaller bolt provided the bolt is to be effectively shorter and the pull of the nuts is to be the same in both cases.

It is obvious, however, that any simultaneous reduction in the bolt sectional area and reduction in the bolt effective length will mean a greater stress on the material of the bolt if the total stretch when the nuts are tightened is to be the same as before.

It may often happen that the bolt stock is sufficiently perfectly elastic to avoid any material permanent set, provided the tension stress in the material of the bolt does not exceed a predetermined value and it will then usually be quite advantageous to have the bolt long and with a sectional size that will limit the stress to this predetermined maximum stress.

The relatively great length is to give it a relatively great elastic elongation, and the arrangement is one to give a live joint of great permanence and having a very uniform clamping force between the bolts and the splice bars.

In the form shown in Figure 4 the head is provided with an outward extension 44 which gives the bar a correspondingly greater upper section modulus. The form requires a relatively long bolt which is desirable when the bolt stock is so highly elastic that it has little or no permanent set.

Figure 5 is a side elevation of Figure 3 and also illustrates that the foot members may be recessed at 45 adjacent the rail flange in order to provide clearance for the head 46 of a tie spike.

The spike may desirably be turned so that its head does not overlap the rail flange to the extent that is usual at ties that are away from the joint, in order to lessen the requisite depth of the recess 45.

Optionally the foot flange may not extend to the edge of the rail flange and in this event the recessing of the foot flange to provide clearance for a tie spike will not be necessary (see Figure 8).

Figure 6 shows a quite desirable form in which the head is materially heavier than the foot, and in which a washer reinforcement member 47 fits between the head and foot flanges at the bolt, supporting these flange portions against one another.

Preferably the washer makes supporting engagement with the flanges near its outer edges, against the head at the top and against the foot at the bottom, thus functioning as a supporting rib between the head and foot portions of the bar. This rib strengthens and stiffens the bar as a whole.

and prevents vibratory movement between the head and foot members.

Figure 7 shows a form somewhat similar to Figure 4 but with both head and foot members heavier than in the earlier figure and having a somewhat different contour.

Figure 8 shows a form that is particularly desirable with the type of tie-plate illustrated in Figures 9 to 11. Both the inner and outer sides are concaved toward the middle of the bar and the nut is provided with an extension 48 for a square wrench hold.

The foot does not extend outwardly to the edge of the rail flange, sufficient space being left to afford hold for a tie spike.

Figures 9 to 11 illustrate a desirable form of joint that includes a long tie-plate 49 extending across the ties 14 and 15 underneath the ends of the adjoining rails.

The tie-plate 49 is desirably of channel form having sides 50 fitting along the outside edges of the rail flange.

I show the rail raised slightly from the bottom of the channel, as by means of one or more flat cross plates 52 so as to leave some little space 53 at each end of the channel to receive molten metal after the joint members have been assembled, in order to firmly support the rails from the channel. This metal may be poured through suitable perforations 54 in the rail flange. Optionally the ends of the channel member may be anchored to the respective rails.

The ends of the rails may be welded together if desired. This may be done, for example, by using dams 55 and 56 of clay or asbestos upon opposite sides of the space between the rails and pouring molten steel in at the top between the rails. The desirability of preventing movement of the rails by welding them to a plate or welding the ends together must be determined by the conditions present in the individual case.

The splice bars 57 are lighter than are illustrated in any of the other arrangements and function very largely as merely safety equipment to insure strength of the joint if the welding should in any case be defective.

Where the long channel tie plate underneath the rail ends at a joint is anchored to the rails at the ends of the tie plate there will be considerable tension upon the tie plate due to the effect of the rolling trains and exaggerated by reason of the relatively great distance of the tie plate from the neutral axis of the rail. Adequate anchored tie plate support of this character can be made very effective in preventing deflection of the rails at the joint.

The metal between the head portions of the rails will usually be under compression while the joint is supporting a rolling load.

Preferably the channel tie-plate is fastened to the ties by the overlapping heads 58 of spikes that enter the ties at the sides of the

channel, similar to the usual spiking between the rail flanges and ties away from the joint.

This permits free running of the rails and tie-plate with respect to the ties which would be difficult or impossible if the tie-plate were spiked directly to the ties as in the form of tie-plate shown in the other figures, where each tie-plate forms a seat individual to the ties and is spiked to the ties.

It is evident that the service conditions, commercial considerations, the available material, equipment and type of labor, the relative ease of assembly and disassembly,—are all variant factors to be taken into account when determining which one of the different forms shown is preferable, and each of these factors may at different times be a predominant factor.

The form of joint illustrated in Figures 9 to 11, for example, while particularly effective as a joint, requires equipment and a grade of labor that is thus far frequently only inadequately available. This condition is being changed however by the present rapid progress in the art of easily providing superheated molten steel in small quantities whether by the thermite process or by the use of small electric furnaces and by the progress in the art of easily cutting out rail sections for replacement.

It will be noticed that in addition to the basis of computation of the comparative section moduli as above there is another basis upon which the structures illustrated could be considered.

In the joint in its entirety I have found that it is desirable to have the metal above the bolt holes slightly heavier and slightly stronger to resist transverse bending strain than the metal below the bolt holes. This is true generally but it is desirable also to have the section modulus of the metal above the bolt holes higher than that of the metal below the bolt holes considered with respect to the axis of each bolt hole, or the line of bolt holes as the axis. This not only gives strength in the upper part of the joint in its entirety to resist bending and crushing straings transverse to the rail web, but gives an additional weight and strength of metal close to the rail head to withstand the impacts transmitted to it initially from the rail heads.

In view of my invention and disclosure variations and modifications to meet individual judgment or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:

1. A rail joint comprising rails having

- abutting ends, and a pair of cooperating splice bars included by vertical planes that are determined by the outer edges of the rail flanges, each bar having a head engaging the rail head and a foot engaging the rail flange and the upper section modulus of the two bars considered together materially greater than the lower section modulus therof. 5
2. A rail joint comprising rails having abutting ends, and a pair of cooperating splice bars included by vertical planes that are determined by the outer edges of the rail flanges, each bar having a head engaging the rail head and a foot engaging the rail flange and the center of gravity axis of the two bars 10 materially above a horizontal middle axis thereof, that is materially higher than midway between the uppermost and lowermost fibers of the bars. 15
3. A rail joint comprising rails having abutting ends, and a pair of cooperating splice bars included by vertical planes that are determined by the outer edges of the rail flanges, each bar having a head engaging the rail head and a foot engaging the rail flange, 20 in combination with bolt members clamping the bars to place and interfitting arcuate bearing surfaces of and between the bars and said members. 25
4. A rail joint comprising rails having abutting ends, and a pair of cooperating splice bars included by vertical planes that are determined by the outer edges of the rail flanges, each bar having a head engaging the rail head and a foot engaging the rail flange, 30 in combination with bolt members clamping the bars to place, each bolt member having a head making ball and socket engagement with one bar and a nut making ball and 35 socket engagement with the other. 40
5. A rail joint comprising rails having abutting ends, and a pair of cooperating splice bars included by vertical planes that are determined by the outer edges of the rail flanges, each bar having a head engaging the rail head and a foot engaging the rail flange, 45 in combination with bolt members clamping the bars to place, each bolt member having a head making ball and socket engagement with one bar and a long nut adapted to make 50 ball and socket engagement with the other bar at either end of the nut and threaded from one end thereof for a portion only of its length, the remaining portion of the length 55 thereof being adapted to pass the threaded end of the bolt without making screw engagement therewith. 60
6. A rail joint comprising rails having abutting ends, and a pair of cooperating splice bars included by vertical planes that are determined by the outer edges of the rail flanges, each bar having a head engaging the rail head and a foot engaging the rail flange, 65 in combination with four bolt members clamping the bars to place and located one 70 near each end of the bars and one near each rail end, the bolts at the rail ends being of greater effective length than those at the bar ends. 75
7. A rail joint comprising rails having abutting ends, and a pair of cooperating splice bars included by vertical planes that are determined by the outer edges of the rail flanges, each bar having a head engaging the rail head and a foot engaging the rail flange, 80 in combination with four bolt members clamping the bars to place and located one near each end of the bars and one near each rail end, the bolts at the rail ends being of alloy steel and those at the bar heads of carbon steel. 85
8. A rail joint comprising rails having abutting ends, a pair of cooperating splice bars included by vertical planes that are determined by the outer edges of the rail flanges, having web portions near the rail web and outwardly extending head and foot flanges that respectively engage the rail head and rail flange, the upper section modulus 90 of the two bars being materially greater than the lower section modulus thereof, washer members fitting the space between the head and foot flanges supporting one flange against the other, and bolt members holding the washer members and the splice bars to place. 95
9. A rail joint comprising rails having abutting ends, and a pair of cooperating splice bars included by vertical planes that are determined by the outer edges of the rail flanges, each bar having a head engaging the rail head and a foot engaging the rail flange and the upper section modulus of the two bars materially greater than the lower section modulus thereof, in combination with a long tie-plate under the bottoms of the ends 100 of the rails and firmly anchored to one rail at one end and to the other rail at the other end. 105
10. A rail joint comprising rails having abutting ends, and a pair of cooperating splice bars included by vertical planes that are determined by the outer edges of the rail flanges, each bar having a head engaging the rail head and a foot engaging the rail flange and the upper section modulus of the two bars materially greater than the lower section modulus thereof, in combination with a long channel tie-plate seating the adjoining 110 ends of the rails, having sides fitting the edges of the rail flange and anchored at one end to one rail and at the other end to the other rail. 115
11. A rail joint comprising rails having abutting ends, and a pair of cooperating splice bars, each bar having a head engaging the rail head and a foot engaging the rail flange, in combination with pairs of bolt 120 members clamping the bars to place and located one pair near the rail ends and one pair farther from the rail ends, the bolts at the rail ends being of greater effective length than those farther from the rail ends. 125 130

12. A rail joint comprising rails having abutting ends, a pair of cooperating splice bars each bar having a head engaging the rail head and a foot engaging the rail flange
5 in combination with bolt members clamping the bars to place and located one pair near the rail ends and one pair farther from the rail ends, the bolts near the rail ends being of alloy steel and those farther from the rail
10 ends of carbon steel.
13. In a rail joint, rails having abutting ends, a pair of cooperating splice bars of substantially equal height and sectional area having upper and lower flanges and bolts to
15 hold the splice bars in position, the relation of the bolt positions, and flange positions being such that there is more flange metal in the spliced bars above the axis of the bolts than below the axis of the bolts.
14. In a rail joint, rails having abutting ends, a pair of cooperating splice bars having bolt holes through the splice bars and flanges above and below the holes and bolts adapted to hold the splice bars together about the
20 rails at the joint, the relations of the parts being such that in each splice bar the kinetic moment of the metal above the bolt axis with respect to the bolt axis is greater than the kinetic moment of the metal below the bolt
25 axis with respect to the bolt axis.
15. In a rail joint, rails having abutting ends, a pair of cooperating splice bars having flanges and having the webs nearer the outer limits of their flanges than the inner limits
30 of their flanges to artificially lengthen the bolts for the purpose of giving bolt resilience and bolts passing through the webs to hold the splice bars in position against the webs.
16. A rail joint comprising two rails having abutting ends, a pair of cooperating splice bars having web portions near the rail webs and outwardly extending head and foot flanges that respectively engage the rail head and rail flange, washer members fitting the
35 space between the head and foot flanges and supporting one flange against the other and bolt members holding the washer members and splice bars to place.
17. A rail joint comprising two rails having abutting ends, a pair of cooperating splice bars having web portions near the rail webs and outwardly extending head and foot flanges that respectively engage the rail head and rail flange, the upper section modulus of
40 the two bars being materially greater than the lower section modulus thereof, washer members fitting the space between the head and foot flanges and supporting one flange against the other and bolt members holding the washer members and splice bars to place.

EUGENE W. CARUTHERS.
